US00D588128S

(12) **United States Design Patent**
Whitmore et al.

(10) **Patent No.:** US D588,128 S
(45) **Date of Patent:** ** Mar. 10, 2009

(54) **PARALLEL ELECTRO-OPTICAL
TRANSCEIVER**

(75) Inventors: **Barry Whitmore**, Albuquerque, NM (US); **Howard Milburn**, Albuquerque, NM (US)

(73) Assignee: **Emcore Corporation**, Albuquerque, NM (US)

(**) Term: **14 Years**

(21) Appl. No.: **29/286,011**

(22) Filed: **Apr. 18, 2007**

(51) **LOC (9) Cl.** 14-02

(52) **U.S. Cl.** D14/358

(58) **Field of Classification Search** D13/149, D13/184; D14/240, 242, 302, 314, 348-355, D14/357-358, 363; 360/79.01, 97.03, 133; 361/658, 725, 752; 369/75.11, 272.1, 273; 379/25, 93.09, 156, 220.14, 338-339, 441, 379/900

(57) **CLAIM**

The ornamental design for a parallel electro-optical transceiver, as shown and described.

DESCRIPTION

FIG. 1 is a top, front and left side perspective view of a parallel electro-optical transceiver, showing my design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom plan view thereof.

The phantom line showing of environment is for illustrative purposes only.
